MOUNTING FOR WINDOWS, DOORS, AND
THE LIKEChester C. Sidwell, Pico, Calif., assignor of one-
half to Lester L. Sidwell, Pico, Calif.

Application June 6, 1934, Serial No. 729,246

3 Claims. (Cl. 20—24)

This invention relates to a mounting for closures, such as windows, doors, and the like, and has as its primary object the provision of a support for vertical closures of the type which are advanced edgewise in and out of their closing position.

Another object is to provide a closure mounting of the above character in which the use of tracks and guide ways is obviated.

10 Another object is to provide a hanger for dependent closures embodying an arrangement of links adapted to permit horizontal rectilinear movement of the closure embodying a construction whereby a balance is maintained throughout the length of movement of the closure and whereby the latter will normally remain at rest in any position throughout the length of its path of travel.

20 Another object is to provide a closure and a mounting therefor which is especially applicable for use in a confined and limited space.

With the foregoing objects in view, together with such other objects and advantages as may subsequently appear, the invention resides in the 25 parts and in the combination, construction and arrangement of parts hereinafter described and claimed, and illustrated by way of example in the accompanying drawing, in which:

Fig. 1 is a view in front elevation of the closure 30 mounting showing it in its normal position:

Fig. 2 is a view in front elevation of the closure mounting showing it as disposed with the closure in a partly open position:

Fig. 3 is a detail in horizontal section taken on 35 the line 3—3 of Fig. 2:

Fig. 4 is a view in end elevation as seen in the direction of the arrow 4 in Fig. 1;

Fig. 5 is a view in end elevation as seen in the direction of the arrow 5 in Fig. 1:

40 Fig. 6 is a detail in horizontal section taken on the line 6—6 of Fig. 1.

Referring to the drawing more specifically A indicates a supporting frame which may be of any suitable construction and which is here shown as comprising an overhead horizontally extending beam 8 supported on spaced uprights 9 and 10 which latter form the vertical side frame members of an opening B. A depending closure C is designed to be moved edgewise to effect opening or closing of the opening B, and which closure is suspended from a mounting D embodying the present invention. As here shown the mounting D includes a horizontally extending metallic bar 11 which is rigidly secured to a side face of the beam 8 as by bolts 12 and 13 and

to which bar is secured by pivots 14 and 15 a pair of upwardly extending links 16 and 17 the upper ends of which are connected by pivot pins 18 and 19 to a pair of horizontal tie bars 20.

The distance between the centers of the pivots 14 and 18 of the link 16 corresponds to the distance between the centers of the pivots 15 and 19 of the link 17, and the distance between the centers of the pivots 14 and 15 on the bar 11 corresponds to the distance between the centers of 10 the pivots 18 and 19 on the bars 20 whereby on moving the links 16 and 17 on the pivots 14 and 15 the links will be maintained in parallel relation with each other, and likewise the bars 20 will be maintained in parallel relation with the 15 fixed bar 11.

In carrying out the present invention a toothed segment 21 is provided in the connection between the link 17 and the bars 20 the segment being disposed concentric with the axis of the pivot 19 20 and rigidly affixed to the link 17 so as to move with the latter relative to the bars 20 on rocking the link 17. The teeth of the segment 21 are presented toward the ends of the bars 20 which protrude past the upper end of the link 17 and 25 intermesh with a companion toothed segment 22 carried by a pivot 23 on the bars 20, and connecting with the segment 22 is a link 24 which extends downwardly and is connected by a pivot 25 to one end of a horizontal bar 26 the other end 30 of which is connected by a pivot 27 to an upwardly extending link 28 connecting with the pivot pin 18 at the upper end of the link 16.

The distance between the centers of the pivots 23 and 25 corresponds to the distance between 35 the centers of the pivots 27 and 18 of the link 28, and likewise to the centers of the pivots at the ends of the links 16 and 17. The distance between the centers of the pivots 25 and 27 at the ends of the bar 26 corresponds to the distance between 40 the centers of the pivots 18 and 23 on the bars 20, and which distances exceed that of the distances between the pivots 14 and 15 on the fixed bar 11 and also of the pivots 18 and 19 on the movable bar 20.

45 On rocking movement being imparted to the links, which manifestly will swing collectively on movement being imparted to either one or more of the links, the bars 20 and 26 will be maintained in parallel relation with the bar 26 moving 50 on a rectangular path of travel while the bar 20 will move with a combined horizontal and vertical motion.

The closure C is carried by the bar 26 to depend therefrom by hangers 29 and 30 connected 55

to the upper end portion of the closure C and attached to the bar 26 adjacent the ends of the latter.

The mounting D is arranged in such position 5 relative to the opening B that when the links 16, 17, 24 and 28 extend vertically the closure C will be positioned to cover the opening B as particularly shown in Fig. 1.

It will now be seen that the links 16 and 17 10 are pivotally carried at their lower ends by the support A and with the tie bar 20 connecting the upper ends thereof constitute the elements of one straight line motion device, while the links 24 and 28 carrying the closure C constitute the 15 elements of another straight line motion device which is supported and carried by the first named straight line motion device, and that the toothed segments 21 and 22 serve as a means for counteracting the movement of one of the 20 straight line motion devices relative to the other.

It will be understood that while the links 16 and 17 are shown as pivoted to the bar 11 they may obviously be connected directly to the support A, and likewise that the lower ends of the 25 links 24 and 28 may be pivotally connected directly to the closure C.

In the operation of the invention when it is desired to open the closure C a horizontal end- 30 wise pressure is imposed thereon, such as to effect longitudinal shifting of the bar 26, which in the arrangement here shown may be effected in either direction and which movement of the bar 26 imparts swinging movement to the links 24 and 28 relative to the bar 26 by reason of 35 their pivotal connection with the upper bar 20 and the latter's engagement with the links 16 and 17.

As the link 24 rocks, a corresponding movement is imparted to the toothed segment 22 and 40 is transmitted by the latter to the segment 21 so as to effect a corresponding rocking movement of the latter and of the link 17 but in a direction opposite that of the link 24. This movement of the links 24 and 17 causes the bar 45 20 to move downwardly and longitudinally and also effects rocking of the links 16 and 28 in opposite directions with the link 16 extending parallel with the link 17, and the link 28 extending parallel with the link 24.

An important feature of the invention resides 50 in the fact that by reason of the interconnection between the segments 21 and 22 downward pull on the links 24 and 28 when the latter are inclined from the vertical, tending to cause the 55 links to move to a horizontal position, is neutralized by this downward pull exerting through the segments an upward thrust on the link 17 such as to counteract the load on the links 24 and 28, thereby establishing a balance whereby 60 the closure will remain at rest at any position in the limit of the path of travel permitted by the link and segment arrangement.

This balance is effective throughout the length 65 of travel of the closure and accordingly the amount of work required to move the closure from either its open or closed position, or in either direction from an intermediate position, will be the same and there will be no tendency for the closure to run free under momentum, 70 thus reducing to a minimum any possibility of the closure slamming against any stop that may

be provided therefor after it has been freed of the opening or closing pressure imposed thereon.

By thus mounting the closure its movement will be silent and will be characterized by a gliding motion and such movement may be effected without the aid of any track or guide other than the guiding action afforded by the link structure D.

Manifestly the closure C may be of any suitable construction and may comprise a door or a window of any desired fabrication. The invention, however, lends itself particularly to the mounting of windows in small dwellings where the wall thickness is such as to inhibit the mounting of the ordinary sliding sash between wall studdings, 15 since by the arrangement here shown the closure C may comprise a sheet of glass suspended directly from bar 26 and accordingly does not necessarily require a sash frame.

Furthermore by the link arrangement here 20 shown but little space is required above the support A for the member D.

However, it will be understood that the invention is applicable to various uses such for example as garage doors, elevator doors, railway 25 car doors and various other closures of the type which are moved edgewise in and out of their closed position.

While I have shown and described a specific 30 embodiment of my invention I do not limit myself to the exact details of construction and arrangement shown but may employ such changes and modifications as come within the meaning and scope of the appended claims.

I claim:

1. In a closure mounting, a pair of dependent links, a closure carried on the lower ends of said links, a tie bar connecting the upper ends of said links, upwardly extending links directly supporting said tie bar adapted to permit longitudinal and vertical movement of said tie bar, and means inter-connecting one of said tie bar supporting links and one of said dependent links for maintaining said tie bar and links stationary at any position throughout the lengths of the paths of travel thereof.

2. In a mounting for a vertically hung closure, a support, a pair of upwardly extending links pivotally carried by said support, a tie bar connecting the upper ends of said links, a second pair of links pivotally carried by said tie bar and depending therefrom; a horizontal bar connecting the lower ends of said last named links, a closure suspended from said last named bar, and means inter-engaging one link of each pair of links whereby rocking movement of one of the links in one direction will tend to rock the other link in the opposite direction.

3. In a closure mounting, a support, a pair of upwardly extending links pivotally carried by said support, a tie bar connecting the upper ends of said links, a second pair of links pivotally connected to said tie bar and depending therefrom, a closure carried by said last named links and exerting a downward thrust thereon, and a pair of intermeshing toothed segments one of which is connected to a link of the first named pair and the other of which is connected to a link of the second named pair.
